UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

NEEDLE-CLAMP FOR SEWING-MACHINES.

1,203,895.

Specification of Letters Patent.

Patented Nov. 7, 1916.

Application filed December 11, 1911. Serial No. 664,972.

To all whom it may concern:

Be it known that I, JAMES R. MOFFATT, a citizen of the United States, residing at Chicago, in the county of Cook, State of Illinois, have invented certain new and useful Improvements in Needle-Clamps for Sewing-Machines, of which the following is a description, reference being had to the accompanying drawings and to the letters and 10 figures of reference marked thereon.

My invention relates to needle holders for sewing machines, and especially to a needle clamp or holder for the needles of a multiple needle sewing machine, in which the needles are arranged oblique to each other respecting the line of feed.

The object of the invention is to provide a simple and effective needle-clamping device for accurately adjusting and rigidly holding 20 the needles in a multiple needle sewing machine, and it consists in the matters herein-after described and referred to in the appended claims.

The invention is illustrated in the accompanying drawings, in which,—

Figure 1 is a side view of a portion of a needle bar with the holder and needles applied thereto; Fig. 2 is a sectional plan on the line 2—2 of Fig. 1; and Fig. 3 is a vertical section on line 3—3 of Fig. 2.

In these drawings, the needle bar is shown at 1, and has its lower end formed with a central opening to receive the shank or upper end of the central needle 2, this needle 35 being clamped in position by the screw 3, the end of which is threaded into the threaded opening through one side of the needle bar, the head of said screw being countersunk into the collar 4, which is clamped to the 40 needle bar by the screw 5. This collar 4 fits on the lower end of the needle bar, being adjustably held thereon by the clamping screw 5, and has vertical openings to receive the shanks of the other needles 2, these needles 45 being clamped in place by the screws 6 threaded into the collar. A plate 7 surrounding the needle bar and screwed to the collar 4 by screws 8, serves as an abutment for the upper ends of the outer needles, and insures 50 their being set at the proper height. By this

arrangement, it will be seen that I have produced a simple, effective, rigid and accurate needle clamp or holder.

Having thus described my invention, what I claim as new and desire to secure by Letters Patent, is:—

1. In combination with the needle bar, a collar clamped thereon having recesses for the needle shanks, recesses extending horizontally into said collar arranged at an angle to a line joining the needles, and clamping screws secured in said recesses and bearing upon said shanks, and a plate on top of said collar and secured thereto against which the upper ends of the shanks abut. 60

2. In combination with the needle bar, a collar clamped thereon having recesses for the needle shanks, recesses extending horizontally into said collar arranged at an angle to a line joining the needles, clamping 70 screws secured in said recesses and bearing upon said shanks, and a plate on top of said collar and secured thereto, against which the upper ends of the shanks abut, said needle bar having a central vertical recess to receive the shank of a needle, and a screw having its inner end threaded through the needle bar and bearing on said shank. 75

3. The combination of a needle bar having a vertical recess in its lower end for the reception of a shank of a needle, a needle clamping collar on the lower end of the needle bar, means for clamping the shank of the needle in the recess in the needle bar, means for clamping said collar to said needle bar, said clamping collar being provided with needle holding recesses upon opposite sides of the needle bar, clamping devices for holding the needles in said recesses, said clamping devices being arranged so as to 80 operate at an angle to a line joining the needle recesses and a plate on top of said collar and secured thereto against which the upper ends of the shanks of the needles passing through the clamping collar abut. 85

4. In combination, a needle bar having a vertical recess in its lower end for the reception of the shank of a needle, a needle clamping collar on the lower end of the needle bar, means for clamping the shank of 100

the needle in the recess of the needle bar, an oppositely disposed screw for holding the needle clamping collar to the needle bar, said clamping collar being provided with needle-holding recesses upon opposite sides of the needle bar, and clamping devices for holding said needle in said recesses, said clamping devices being arranged horizontally and op-

erating at an angle to a line joining the needle recesses.

In testimony whereof I affix my signature, in presence of two witnesses.

JAMES R. MOFFATT.
